UNITED STATES PATENT OFFICE.

ROBERT C. COLE, OF HARTFORD, CONNECTICUT, ASSIGNOR TO THE JOHNS-PRATT COMPANY, OF HARTFORD, CONNECTICUT, A CORPORATION OF CONNECTICUT.

ELECTRIC SWITCH.

1,127,408.

Specification of Letters Patent.

Patented Feb. 9, 1915.

Application filed March 17, 1913. Serial No. 754,923.

To all whom it may concern:

Be it known that I, ROBERT C. COLE, a citizen of the United States, residing at Hartford, in the county of Hartford and State of Connecticut, have invented a new and useful Improvement in Electric Switches, of which the following is a specification.

This invention relates to a reciprocating snap electric switch of the push button type, which is particularly adapted for main line service. Such a switch is customarily inclosed in a box for its protection and for preventing accidental engagement with any live parts of the switch or the circuit wires.

The object of the invention is to provide a thoroughly insulated, quick acting multiple break switch of this character which can be located without effecting its operation so that the service wires may enter the box from either the top or the bottom, according to the arrangement of the wires where the switch is used, and that can be sealed in the box so as to protect the company from fraudulent manipulation and the customer from possibility of accidental contact with live parts, but can be operated by anyone at any desired time with the cover opened or closed, which cover, for the purpose of examining the switch or the fuses with which the circuit is protected, can be opened and closed without altering the circuit conditions, whether the switch be opened or closed. In attaining this end, the

stationary conducting contacts to which the circuit wires are joined are mounted in pockets in an insulating base which has provision for the insertion of fuses into the circuit. The movable conducting contacts are mounted upon an insulating block which is movable in and out on a guide post that is supported by the base. The movable contact block is normally thrust out by a spring located on the post between the base and the block and is adapted to be forced in against the pressure of the spring by a push button. When the block is pushed in, it is held by a latch on the post, which latch is designed to be released by a push button and when released the block and the movable contacts are thrown out by the spring. The base with the fixed contacts and the block with the movable contacts are located in a box which has a cover that may be opened and closed. The push buttons by means of

which the block is pushed in for closing the circuit and the latch is released so that the block may be thrown out for opening the circuit, are movably mounted in the cover and are independent of any of the other parts. This permits the switch to be operated for opening and closing a circuit with the cover closed, and allows the cover to be opened for the purpose of ascertaining the condition of the switch or of the fuses without disturbing the circuit, that is, the cover may be opened and closed whether the circuit is opened or closed without changing the relation of the conducting parts, and the switch may be operated to alter the condition of the circuit when the cover is opened as well as when the cover is closed.

Figure 1 of the accompanying drawings shows a plan of the switch with the cover removed. Fig. 2 shows a vertical section of the same on the plane indicated by the dotted line 2-2 on Fig. 1. Fig. 3 shows an end elevation with the casing cut in section.

The base 1 may be made of porcelain or any other desired insulating material. Spring contact fingers 2 are located in pockets in the base. The contact fingers on one side are connected with terminal lugs 3 and on the other side are connected with the center contacts 4 of the fuse receptacles 5, the outer contacts of which are connected with terminal lugs 6.

Supported at the center of the base and projecting outwardly is an angular post 7. Movable up and down on this post is a block 8 of insulating material. Secured to the block and projecting inwardly are contact blades 9. The blades on each side are electrically joined so that when the block is pushed in the movable blades will engage with the fixed fingers and close the electrical circuit through the switch. When the block is out the blades are withdrawn from the fingers a sufficient distance to safely open the circuit. On the post and thrusting between the base and the block is a spiral spring 10. This spring normally thrusts the block outwardly, a pin 11 thrusts through the post limiting the outward movement of the block. In a slot in the upper end of the post is a pivoted latch 12. The inner end of this latch is thrust out by a spring 13 so that when the block is pushed in the shoulder 14 on the latch will engage the

edge of the block and hold it from outward movement, as shown in Fig. 3. When the latch is moved so as to release the block, the spring quickly throws the block outward to the position seen in Fig. 2 and instantly opens the circuit.

The switch is located in a box 15 which is desirably formed of sheet steel with insulating bushings 16 in the openings 10 through which the circuit wires are designed to pass. Hinged to the box is a cover 17 which is also desirably stamped from sheet steel. A spring tongue 18 is desirably arranged so as to pass through an opening in the cover on the side opposite the hinge in order to hold the cover closed and permit it to be sealed if desired.

Movably mounted in the cover is a push button 19 which is normally thrust out by 20 a leaf spring 20 that is attached to the inside of the cover. Adjacent to this button and movably mounted in the cover is a button 21 that is normally thrust out by a spring 22. The button 19 is so arranged 25 that when it is pushed in it will engage the outer surface of the insulating block bearing the movable contacts or the metal bushing 23 set into that block, and will force it inward and cause the blades on the block to 30 engage the contacts on the base. When the block is pushed in by this button sufficiently far for the blades and contacts to make proper engagement, the latch 12 that is supported by the guiding post springs out 35 and engages the block or metal bushing in the block so as to hold the parts in the positions to which they are moved. The button 21 is arranged so that when pushed in it will engage the outer end of the latch 12 40 and move it in such manner that it will release the block and allow the spring to throw it out and open the circuit.

This switch can be located according to the condition of the wires, either end up, 45 and the movements are sufficiently rapid

and great to meet the requirements for safety. The conducting parts are inclosed and protected in such manner as to eliminate the possibility of accidental contact therewith. The switch can be operated at 50 any time by anyone without danger, and the cover can be sealed so as to prevent access to the interior. The cover may be opened when desired without disturbing the circuits for permitting inspection of the fuses 55 or the insertion or removal of a fuse, and the switch will remain in the condition in which it is set, whether the cover is opened or closed and yet it can be operated with ease whether the cover is opened or closed. 60

The invention claimed is:

An electric cut-out comprising an insulating base, conducting clips fixed on the base, a post extending outwardly from the base, a block movable on the post toward and from the base, conducting blades carried by said block, a spring on the post for moving the block from the base, a latch pivotally mounted in the post and adapted to engage and temporarily hold the block in its inner 70 position with the spring tense and the blades engaged with the clips, a box containing said switch parts, a cover for closing the box, a push button mounted on the cover and adapted when the cover is closed 75 to be engaged with and to push the block toward the base and cause the engagement of the blades with the clips, and a push button mounted on the cover and adapted when the cover is closed to be engaged with and to 80 release the block retaining-latch, said push buttons being disconnected from any of the switch parts so that the cover by which they are carried can be opened and closed without affecting the circuit conditions.

ROBERT C. COLE.
